UNITED STATES PATENT OFFICE.

SYLVESTER J. MITCHELL, ALFRED D. GABBERT, AND JOHN W. BLATTER, OF GRAND JUNCTION, COLORADO.

PRUNING LADDER.

Application filed March 21, 1922. Serial No. 545,498.

To all whom it may concern:

Be it known that we, SYLVESTER J. MITCHELL, ALFRED D. GABBERT, and JOHN W. BLATTER, citizens of the United States, residing at Grand Junction, county of Mesa, and State of Colorado, have invented certain new and useful Improvements in Pruning Ladders, of which the following is a specification.

Our invention relates to platform ladders designed to be used for pruning and picking purposes in orchards and the like, and it has particular reference to a portable ladder so mounted as to be readily accessible at all times and which may be utilized in moving the ladder member from tree to tree or various points, without moving the base upon which the ladder is mounted.

The primary object of the invention is to provide a pruning and picking ladder which is readily transportable, efficient in operation, and which, when set up, can be employed in such manner that the ladder may be moved from point to point without disturbing the base upon which the ladder is mounted.

Another object of the invention is to provide a ladder of this character in which the ladder is so mounted in relation to its support that it may be folded thereonto, extended therefrom, and moved relative thereto without disturbing in any way the support.

With these and such other objects in view, as will be apparent from the description, our invention resides in the novel combination, construction, and arrangement of parts hereinafter described and claimed, and illustrated in the accompanying drawings, in which—

Figure 1 is a side elevation of the preferred form of the invention;

Figure 2, a top plan view thereof;

Figure 3, a transverse section through the support showing the ladder in extended position; and

Figure 4, a similar section showing a ladder when disposed in folded position.

In detail, the invention comprises a relatively large rectangular base 1, suitably supported on longitudinal beams 2, and having mounted thereon at opposite ends transverse beams 3, between which are disposed at opposite side edges of the base longitudinally extending rods 4 supported

on the end beams 3 in suitable retaining members 5. By this construction the rods 4 are supported in spaced relation from the base 1 and their central portions are supported against sagging by means of the brace bearings 6 disposed substantially centrally of the base.

Inclined ladders 7 are pivoted at their lower ends on the rod 4 at one side of the base, the connection being such as to permit of the ladders being moved longitudinally of the base on the rod, and while in the present instance we have but two ladders, it is obvious that any number may be employed as desired. The ladders are supported when in raised position by means of guy wires 8 suitably connected to one of the rungs of the ladder, indicated at 9, adjacent the upper end thereof, and these wires extend transversely across the base and are connected at their opposite ends to sleeve members 10 longitudinally slideable on the opposite rod 4, whereby when the ladders are moved longitudinally of the support the guy wires may be carried likewise with perfect freedom of movement.

When in folded position, the ladders 7 are folded upon the base 1 with their outer ends resting on the rod 4 which carries the guy wire sleeve members. In this preferred form, the base 1 is shown as a framework adapted to be rested on the ground at the base of the trees and the like, but it is obvious that the same may be supported on a wagon and moved from place to place or mounted on wheels or skids as desired, without in any way departing from the scope of the invention.

While we have described and illustrated in this preferred form, certain details of construction, we do not intend to limit ourselves to these, but any such may be used as will fall within the scope of the invention as claimed.

We claim:

A pruning ladder comprising a portable, flat, rectangular base adapted to be mounted on a wagon body, transverse beams at opposite ends thereof, longitudinally disposed rods carried by said beams along opposite sides of the base and in spaced relation thereabove, a ladder pivoted at its lower end on one of said rods and foldable over said base with its upper end adapted to be supported on the other of said rods,

the length of said ladder equalling the width of the base, said ladder being slidable on its rod longitudinally of the base, a sleeve rotatably and slidably disposed on the opposite rod, and a guy wire connected at one end to said sleeve and at the opposite end to an upper rung of the ladder, whereby said ladder, wire, and sleeve may be moved longitudinally of the base and maintained

in raised position, the length of said wire ¹⁰ being such as to dispose said ladder when raised inclined outwardly of the base.

In testimony whereof we affix our signatures.

SYLVESTER J. MITCHELL.
ALFRED D. GABBERT.
JOHN W. BLATTER.
